UNITED STATES PATENT OFFICE.

CHARLES H. ANDERSON, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

SHELVING.

Application filed June 15, 1925. Serial No. 37,062.

This invention relates to shelving and is more particularly concerned with adjustable shelving which can be made very economically and in knock-down form so that it may be easily and conveniently shipped and which, when assembled, has the parts thereof firmly secured and substantially interlocked together, there being provided smooth and flush ends at each end of the shelves, and said shelves being adjustable to any desired position. This is particularly desirable when the shelving is used for carrying shoes which, in retail shoe stores, are ordinarily enclosed in boxes; and the present invention is designed to improve the construction shown in United States Letters Patent No. 1,381,501, issued June 14, 1921, wherein for the adjustment of the shelves, the filler members at the ends of the shelves have to be replaced with those of different heights, this being in some ways unsatisfactory and requiring the possession of spacing and filling members at the ends of the shelves many of which are not in use at times, or if such filling members are not in the possession of the user of the shelving when a change in adjustment is made, the same must be ordered from the factory.

For an understanding of the invention reference may be had to the following description taken in connection with the accompanying drawings, in which,

Fig. 1 is a perspective view of a shelving unit constructed in accordance with my invention.

Fig. 2 is an enlarged perspective view of the immediate shelf supports used.

Fig. 3 is a fragmentary enlarged horizontal section through one unit and a portion of a contiguous unit.

Fig. 4 is a fragmentary perspective view and section illustrating the front portion of an end of the shelving construction, and

Fig. 5 is a similar view of the rear portion of said end of the shelving unit.

Like reference characters refer to like parts in the different figures of the drawings.

In the construction of the shelving, front posts or pilasters 1 substantially square in cross section, though not necessarily so, are used being spaced apart a distance slightly greater than the length of the shelves to be used, each at its front side having a front facing strip 2 attached, the edges of which

extend beyond the adjacent sides of the posts or pilasters 1. While the strip 2 as shown is a separate piece from the post 1 it may be formed integral therewith if desired. A rear post or pilaster 3 similar to the posts or pilasters 1 are used located back of each pilaster 1 and spaced therefrom each, at its rear side, carrying a facing strip 4 somewhat wider than the strip 2 so that at its edge portions it projects at each side farther beyond the sides of the post or pilaster 3 as shown. To each of the posts or pilasters 1 and 3 at each side thereof a metal channel 5 is attached by means of screws 7, the flanges of said channels being turned inward and the outer sides of the webs of the front channels being flush with the edges of the facing strips 2, while the outer sides of the webs 5 attached to the rear posts or pilasters 3 are located a short distance inward from the edges of the facing strips 4. The webs 7 of these channels are provided with a plurality of short horizontal slots 6 located closely together, the purpose of which will later appear.

The front posts or pilasters 1 and 3 may be connected together in any suitable manner as, for instance, by the lower rail 8, between the lower ends of the front posts or pilasters 1 and the upper cornice rail 9 at the front and between the upper ends of said front posts or pilasters. The front pilasters 1 and the rear pilasters 3 directly back thereof are connected at their upper ends by a bar 10 and at their lower ends by a bar 11 as shown. The specific method of connecting these posts or pilasters forms no part of the present invention and may be similar or like that shown in the pending application, Serial No. 476,151, filed June 9, 1921, by Morris Reigersberg, whereby a detachable connection of the parts is made so that the same may be readily knocked down for shipment and very easily assembled when the destination is reached. Between the front and rear posts 1 and 3 covering boards or panels 12 are located and permanently secured in place, the same lying between the channel members 5 and with their outer sides flush with the outer sides of the webs of said channel members, it being apparent that each end of the shelving unit, comprised as it is of pilasters 1 and 3, facing strips 2 and 4, the channels 5, connecting members 10 and 11

and the covering boards 12, is a permanent unit and is shipped in assembled form. Preferably the boards 12 are of beaver board or like construction though any thin material capable of covering the space between the front and rear pilasters may be used.

The slots 6 in the channels 5 are adapted to detachably receive shelf supports which are formed from metal comprising a flat 10 plate 13 at one end of which a tongue 14 extends, the same at its end being turned upwardly as shown in Fig. 2. This tongue may be inserted through any slot 6 and the shoulders which are formed between the 15 wider plate 13 and the narrower tongue 14 bear against the outer side of the channel so that said plate 13 is held in horizontal position.

The shelves 15 are of rectangular form 20 and are adapted to rest on the shelf supports 13 at their corners. Each shelf 15 at its rear edge has a vertical board or strip 16 secured thereto which extends both above and below the upper and lower sides of the 25 shelf and at each end terminates a short distance from the end of the shelf. When a shelf is located on four of the shelf supports at its corners the ends of the strips 16 abut against the projecting edge portions of the 30 rear facing members 4. That portion of the strip 16 extending below the shelf 15 lies back of the rear shelf supports 13 so that the shelf cannot be moved forward and the ends of the shelf 15 coming in front of the projecting or overlapping edges of the facing 35 plates 4 prevent the shelf from moving backward so that each shelf is practically locked in place and cannot be removed except by elevating the rear portion of the shelf a distance above the shelf supports 13 so that the 40 strip 16 clears the same. It is evident that by reason of the close spacing of the slots 16 the shelf supports may be brought closer together or positioned farther away from 45 each other by merely changing the position of the shelf supports 13 which is very quickly and easily done.

To place two or more of the shelving units in horizontal alignment after one shelving 50 unit is set up, as shown in Fig. 1, it is necessary merely to use an additional member comprising front and rear posts or pilasters 1 and 3 connected by bars 10 and 11 and with the covering boards 12 attached, 55 spacing it the proper distance from the end of the unit already assembled, connect the same with the lower and upper front members 8 and 9, apply the shelf supports 13 and add the shelves thereto. This may be continued indefinitely for additional shelving 60 units as far as may be desired; that is, the intermediate members of the construction serve as supports for shelves at each side thereof. This construction of shelving is 65 very economical to produce and has proved

exceptionally satisfactory for store service use. The invention is defined in the appended claims and is to be considered as comprehensive of all forms of structure coming within their scope.

70 I claim:

1. Shelving construction comprising, two end members each including a front and rear post or pilaster, the front pilaster at its front side having laterally extending portions and the rear pilaster at its rear side likewise having laterally extending portions which extend farther from the sides of the rear pilaster than said laterally extending portions do from the sides of the front 75 pilaster, a vertical channel bar secured to each post or pilaster at each side thereof adjacent said laterally extending portions, each of said channel bars comprising an outer web and inwardly extending flanges, 80 the outer sides of the webs being substantially flush with the edges of the laterally projecting portions on the front pilaster and each web of each channel member being formed with a plurality of closely spaced 85 apart horizontal slots therein, covering boards having their outer sides substantially flush with the outer sides of the webs of the channel members disposed between and located one at each side of said pilasters and 90 secured thereto, means connecting the upper and the lower ends of said front and rear pilasters of each end member, means disposed between and connecting the upper and lower ends of the front pilasters of said 95 shelving unit, shelf supports adjustably mounted in the slots in said channel members, rectangular shelves seated on said shelf supports, and a strip attached to the rear 100 edge of each shelf having portions extending 105 above the upper side and below the lower side of the shelf to which it is attached, substantially as and for the purposes described.

2. A shelving unit comprising, spaced 110 apart end members each including front and rear pilasters, means connecting the upper and lower ends thereof, channel members attached one at each side of and adjacent the front of each pilaster, covering boards 115 having outer sides substantially flush with the outer surfaces of the channel members located between and attached to the pilasters of each end member, each of said channel members being formed with a plurality of 120 closely spaced horizontal slots therein, shelf supports adjustably connected to said channel members in slots thereof, upper and lower rails connecting the front pilasters of 125 said end members, and shelves carried on said shelf supports, substantially as described.

3. A shelving construction comprising, two vertical end members each including front and rear posts, means connecting said 130

front and rear posts of said end members at their upper and lower ends, upper and lower rails connecting the front posts of said end members, metal channels attached at the inner side of each post, shelf supports adjustably mounted thereon, shelves resting on said shelf supports, and covering boards disposed between and at the inner side of the pilasters located flush with said channel members, substantially as described.

4. Shelving construction comprising, vertical end members each including front and rear spaced apart posts, covering boards extending between the posts at each side thereof and attached thereto, means located at each edge of said boards and attached to the posts for adjustably carrying shelf supports, shelf supports adjustably mounted on said means, connections between said end members at their upper and lower ends, and shelves resting on said shelf supports, substantially as described.

5. A construction containing the elements in combination defined in claim 4, combined with facing strips attached to the front sides of the front posts, the edges of which lie substantially in the same vertical planes with the inner side of said covering boards, other facing strips attached to the rear faces of the rear posts having edge portions extending beyond the planes of said inner sides of the covering boards, and a strip attached to the rear edge of each shelf extending both above and below the upper and lower sides of the shelf, substantially as described.

6. Shelving of the character described comprising, two spaced apart end members each including a front post and a rear post located back of the front post, a facing strip attached to the front side of each front post having edge portions extending beyond the sides thereof, channel members located one against each side of each front post or pilaster having an outer web and inturned flanges, the edges of the facing strip lying substantially flush with the outer sides of said channel members, a wider facing strip attached to the rear side of each rear post or pilaster, similar channel members attached one to each side of each rear post or pilas-

ter, covering boards disposed between the channel members on the front and rear posts and attached thereto having their outer sides in substantially the same plane with the outer sides of said channels, means connecting said end members at their upper and lower ends to hold the same in spaced apart relation, shelf supports adjustably mounted on the channel members, and shelves carried by the shelf supports, each of said shelves at its rear edge being provided with a strip having portions projecting above and below the upper and lower sides of the shelf respectively, said strips at their ends substantially abutting the adjacent edges of the facing strips attached to the rear posts or pilasters, substantially as described.

7. In a shelving construction, spaced apart end members having smooth inner sides, means connecting said end members together in spaced apart relation, shelf supports adjustably mounted adjacent the front and rear sides of said end members, a rectangular shelf carried by the shelf supports and means attached to said shelves and to said end members for interlocking the shelves against endwise or forward or rearward movement with respect to said shelf supports, substantially as described.

8. In combination, in a shelving construction, spaced apart end members having substantially smooth and flush inner sides, means connecting said end members to hold the same in spaced apart relation, shelf supports adjustably mounted on said end members at the inner sides and near the front and rear sides thereof, vertical facing strips attached to said end members at their rear sides having inwardly projecting portions extending beyond the inner sides of said end members, a rectangular shelf carried by the shelf supports, and means attached to said shelves located between said facing strips and back of the rear shelf supports acting to hold said shelf from forward movement, said facing strips holding the shelves from rearward movement, substantially as described.

In testimony whereof I affix my signature.
CHARLES H. ANDERSON.
